UNITED STATES PATENT OFFICE

GEORGE H. GILLIGAN, OF PROVIDENCE, RHODE ISLAND, ASSIGNOR TO U. S. RING TRAVELER COMPANY, OF PROVIDENCE, RHODE ISLAND, A CORPORATION OF RHODE ISLAND

RING TRAVELER

Application filed December 10, 1930. Serial No. 501,208.

My invention relates to ring travelers of the horizontal or bow type for use upon spinning or twisting rings.

In this type of traveler the body is arched 5 and terminates at its lower end with horizontally inwardly directed aligned horns at their free ends.

The material for the travelers is automatically cut in length from a metallic strip 10 or rod, and subsequently bent, hardened and polished. The cutting or severing operation leaves the blanks with rough or wire edge terminal faces, which even the final step of polishing frequently fails to eliminate.

15 In the final product the roughness appears at the free ends of the horns which are presented to the ring web as the traveler rides around the ring, and cutting or scoring of the web occurs along a line of continuous contact, 20 and the traveler itself becomes worn, which results in expense by reason of replacements and stoppages.

This wear is very pronounced even when the ends of the traveler are successfully 25 smoothed, and at best present relatively sharp or penetrating projections to the ring web.

The essential objects of my invention are to overcome the disadvantages above advert- 30 ed to, prevent the scoring of the ring by the traveler, assist maintaining the traveler in upright running position, and to effect the desired objects in a simple and inexpensive structure.

35 To the above ends essentially my invention consists in such parts and in such combinations of parts as fall within the scope of the appended claims.

In the accompanying drawings which form 40 a part of this specification,

Figure 1 is a plan of a spinning or twisting ring engaged by my novel traveler,

Figure 2, a fragmentary sectional view of the same taken on line 2—2 of Figure 1,

45 Figure 3, a perspective view of my traveler detached, and

Figure 4 is a detail view of a modified form of my traveler.

Like reference characters indicate like 50 parts throughout the views.

As herein shown 7 represents a ring of the horizontal type commonly employed upon spinning and twisting machines, and comprises a vertical body or web 8, a base 9, and a horizontal top flange 10 extending laterally 55 of both faces of the web.

It is in conjunction with a ring having the type of flange 10 herein above set forth that my traveler 12 is intended to be employed.

The latter is bent up from a substantially 60 flat metallic blank, and comprises an arched body or bow 13, horizontal horns 14, and terminal bearing members consisting of fingers 15, continuous with the free ends of the horns, directed toward the bow, and disposed at substantially right angles to the latter. The bearing faces of the fingers are 65 indicated at 16.

In Figure 2 the traveler is shown applied to the ring in an operating position. 70 Centrifugal force, during movement of the traveler, is in the direction of the arrow, and, therefore, the engaged finger 15 presents a perfectly smooth surface of contact 16 with the web 8, at the point where the impinging 75 power is greatest. Under these conditions also the parallel relation of the contacting fingers 15 to the web tends to assist maintaining the traveler 12 in a horizontal rather than tilting position relatively to the ring. 80

It will be noted that the presence of the members 15 renders impossible the scoring of the ring which centrifugal action would occasion were they absent.

In the modification of my invention shown 85 in Figure 5 the terminal edges 23 of the bearing members or fingers are transversely curved.

Having thus described certain illustrative embodiments of my invention, it is understood 90 that the specific terms employed are used in a descriptive sense only, and are not for the purpose of limitation, the scope of the invention being defined by the appended claims.

I claim:

1. A ring traveler comprising a bow, inwardly directed horns upon the bow lying in the same horizontal plane, and terminal bearing members upon the horns disposed at substantially right angles to the horns and di- 100

rected toward the bow providing a flat bearing surface for the traveler.

2. In combination with the web and flange of a spinning or twisting ring, a ring traveler 5 comprising a bow spanning the ring, horns upon the bow extending towards the web, and terminal bearing members upon the horns disposed at substantially right angles to the horns and directed toward the bow, 10 providing a flat bearing surface for the traveler with the web.

3. A ring traveler comprising a bow, inwardly directed horns upon the ends of the bow, flat bearing members continuous with 15 the ends of the horns extending at substantially right angles to the horns and vertically directed toward the bow.

4. A ring traveler comprising a bow, inwardly directed horns upon the bow, terminal bearing members upon the horns disposed 20 at substantially right angles to the horns and directed toward the bow, providing a flat bearing surface for the traveler, the terminal edges of the bearing members being 25 curved transversely.

In testimony whereof I have affixed my signature.

GEORGE H. GILLIGAN.
